(57) **CLAIM**

The ornamental design for a liquid sample detector as shown and described.

DESCRIPTION

FIG. 1 is a bottom, front, left side perspective view of a liquid sample detector showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.
